UNITED STATES PATENT OFFICE.

SAMUEL H. RANSOM, OF ALBANY, NEW YORK.

DESIGN FOR THE PLATES OF A COOKING-STOVE.

Specification forming part of Design No. 6,727, dated June 24, 1873; application filed April 18, 1873.

To all whom it may concern:

Be it known that I, S. H. RANSOM, of the city and county of Albany, and State of New York, have invented a Design for the Plates of a Cook-Stove, of which the following is a specification:

The nature of my design is fully represented in the accompanying engraving, to which reference is made.

A represents the center ornament of the oven-door, an oval, bulbed-shaped center immediately surrounded by a row or string of beads, surmounted by fan-shaped scroll formation, the lower portion being formed of scrolls, from which hang several pearl-shaped pendants. B represents the ornamentation surrounding the panel of the door, being combination of an inner line of "scale"

work, and an outer line of loops and small crescent-shaped attachments. C C represent ornaments for smaller panels, being a bulb-shaped center surrounded by bead-work, and finished, at the top and bottom and sides, with small scroll projections. D represents center ornament of closet-door, being similar in design to C C, but, in addition, surrounded by an irregularly-shaped flat band, filled on its surface with raised beads.

I do not claim as important the formation or shape of molding.

What I claim as my invention is—

A design for the plates of a cook-stove, substantially in the manner above mentioned.

Witnesses:

S. H. RANSOM.

B. BURTON,
JAS. A. GREIG.
